STACKING DEVICE FOR FOLDING MACHINES

Clifton S. Malott, Jr., Cincinnati, Ohio, assignor to The American Laundry Machinery Company, Cincinnati, Ohio, a corporation of Ohio

Application October 19, 1946, Serial No. 704,401

7 Claims. (Cl. 271—68)

1

This invention relates to stacking machines, such as are used for stacking flat articles of any kind, such as paper sheets or articles made from textile fabrics, e. g., napkins, handkerchiefs, towels or the like, either folded or unfolded. The invention will be described with more particular reference to its use for stacking folded fabric articles as they come directly from the folding machine.

The present stacking machine is of the bottom stacking type. That is, it adds successive articles, one by one, to the bottom of the growing stack, which is supported in upright position and is lifted each time another article is added to its lower end.

One object of the present invention is to generally improve the machine by simpler and more direct operating mechanism for the stack lifting and supporting plates, with the latter so arranged as to move substantially horizontally and in such manner as to enable them to be brought close together to supply wide and solid support for the stack.

Another object is to support the stack at all times in such manner that the articles are properly stacked, with no curled or folded over edges, whether they are thin and limp or thick and heavy.

Still another object is to provide an improved stacking machine in which the stack supporting plates or fingers are pivoted and thus are capable of operation by very simple mechanism, but nevertheless move generally horizontally or at least with minimum vertical motion, because they are pivoted directly and well below their paths of movement.

Another object is to provide improved means for insuring that each article is fed to and actually reaches position upon the lifting plates, even if delivered to them before they are fully down in work-receiving position.

Another object is to slow up the speed of travel of the articles as they reach their positions on the lifting plates, such means being adjustable to be equally effective on either light or heavy articles.

Still another object is to provide an improved stack guide, including means for more positively maintaining the stack upright, with successive articles properly aligned with or piled upon each other.

Another object is to provide improved means for guiding the lifting plate during its up-and-down movement, thus always maintaining it level, and insuring a symmetrical stack.

2

Further objects of the invention in part are obvious and in part will appear more in detail hereinafter.

In the drawings, which represent one suitable embodiment of the invention, chosen solely for purposes of illustration and in no sense of limitation,

Fig. 1 is a transverse sectional elevation on the line 1—1, Fig. 2;

10 Fig. 2 is a side elevation from the left in Fig. 1; Fig. 3 is a detail plan view of a portion of the machine, corresponding to Fig. 2;

Fig. 4 is a detail sectional elevation, on the line 4—4, Fig. 3;

15 Fig. 5 is a detail sectional elevation, on a larger scale, on the line 5—5, Fig. 6;

Fig. 6 is a detail plan view illustrating certain bridging fingers;

Fig. 7 is a detail plan view on the line 7—7, 20 Fig. 2; and

Fig. 8 is a detail sectional elevation, illustrating one of the stack guides.

The stacking machine shown in the drawings includes a suitable frame designed to rest upon the floor, table or other suitable support and consisting of side members 10 connected and strongly braced by cross rods 11 and provided in its lower portion with a horizontal plate 12 which serves as the direct support for the clutch operating mechanism later to be referred to. In suitable bearings 13, 14 mounted respectively upon brackets 15, 16 supported by the frame, is a rotatable shaft 17 provided at one end with a large sprocket wheel 18 driven either from the motor or mechanism of the associated folding machine, shown conventionally in dot-dash lines at 19, Fig. 2, as by a sprocket chain 20 passing over an idler 21.

Upon said shaft is rotatably mounted a longitudinally slidabile sleeve 22 provided at one end with a clutch member 23 and at its opposite end having an enlarged extension 24 which serves as the hub for a small sprocket member 25, which may be connected, as by chain 26 (Fig. 2), and may be utilized to drive or operate a cross folding blade (not shown) in the associated folder 19.

Compression spring 27, housed within the sleeve 22 and surrounding shaft 17 always tends to move sleeve 22 to the right in Fig. 1, thus to engage clutch member 23, rotatable with the sleeve, with its companion clutch member 28, fixed to shaft 17. But the clutch members are normally held out of engagement when the stacking parts are not operating, by a roller 29 mounted upon a lever 30 pivoted at 31 and connected

by toggle links 32, 33 to a shaft 34 having an arm 35 connected by link 36 to the plunger 37 of a solenoid or electromagnetic servomotor 38 supported upon a bracket 39 attached to the main frame. Torsion spring 40, wound around the shaft 34, biases said shaft in the clockwise direction, Fig. 2, thus tending to straighten the toggle links and advance roller 29 into engagement with the track of a cam 41 with which roller 29 cooperates. Fig. 1 shows roller 29 engaged with the cam. Whenever the solenoid 38 is energized the levers 35 and 36 are pulled down, moving roller 29 out of engagement with the cam. This frees the sleeve 22 for motion to the right in Fig. 1 thus causing the clutch members to engage and causing rotation of the sleeve. Solenoid 38 is energized momentarily, at intervals, by a suitable controlling circuit indicated conventionally at 38a, Fig. 1. This circuit, for example, may be the controlling circuit of the folding machine which causes operation of its folding blade as each article reaches the folding position. But because the impulse for that purpose is but momentary, whenever roller 29 is disengaged from the cam and the sleeve 22 begins to rotate, the solenoid 38 is deenergized and the next time the recess of the cam track in cam 41 comes around, the roller 29 enters it and the cam, cooperating with the roller, returns the sleeve endwise, against the force of spring 21, to its original position, thus uncoupling the clutch.

Thus the mechanism described essentially is a one-revolution control mechanism for causing one revolution of sleeve 22 by constantly rotating shaft 17, each time the electromagnet is energized.

Sleeve 22 supports three cams, numbered respectively 42, 43, 44, the purpose of which is to operate the stacking device.

The stacking device includes two sets of generally horizontally extending plates or fingers 45, one on each side of the machine, the two sets of fingers extending toward each other, and a lifting plate or plates 46 which normally lies beneath the stack supporting plates, when the stacking parts are not operating as shown in full lines, Fig. 1.

The stack supporting plates or fingers 45 are carried by tubular cross members 47, extending longitudinally of the machine and attached to side arms 48, two or more for each set of fingers, the side arms extending downwardly and being attached at their lower ends to collars 49 fixed to shaft 50, each of which is provided with a horizontally extending arm 51 having a roller 52 traveling upon one or the other of the cams 42, 44. As shown in Fig. 1 the two arms 51 cross each other, the arm attached to the left-hand shaft 50 extending over to the right-hand cam 44 and that attached to the right-hand shaft 50 extending over to the left-hand cam 42. A tension spring 53 connects two small fingers 54, one attached to each shaft, said spring constantly exerting a bias tending to move the two sets of arms 48 toward each other and the stack supporting plates or fingers to their full line position, Fig. 1.

The lifting plates 46 are mounted upon angle brackets 54a each supported by a vertical, cylindrical rod or pillar 55, the two rods being attached to a plate 56 having a depending bifurcated stem 57, in which is a roller 58 traveling upon cam 43 and held to it by the tension of two tension springs 59 connected at their upper ends to bent arms 60 (Fig. 7) and at their lower ends to eyes 61 (Figs. 1 and 2) on plate 12. The arms 60 are attached to the stem 57 and are bent so that the springs

will clear the cams and the parts of the sleeve between them.

The two rods 55 travel between and are each guided by four rollers in two pairs, marked respectively 62, 63, Fig. 2. Rollers 62 for each post are mounted on a plate 64 rigidly fastened to a support 65 mounted on a frame bracket 66, while rollers 63 for each post are mounted upon a plate 67 which is adjustable along a slot 68 in plate 64 so that the two sets of rollers for each post can be moved toward each other for adjustment to take up slack or wear and to insure true vertical motion of the rods and the lifting plate members 46 which they carry.

The stack of articles being formed is guided in its upward movement and to some extent is supported, as against toppling over laterally, by upwardly-extending posts or guide members 69, each of which is provided with an auxiliary rod 70 secured at its lower end to the post and at its upper end being bent laterally to provide an arm 71 which enters an opening 72 near the top of the post, against the yielding resistance of a compression spring 73. These rods depress themselves into the sides or edges of the stacked articles, and guide them and prevent the pile from toppling.

Conveyor belt 74, of which there is one, traveling down the center of the stacking machine, as shown in Figs. 1 and 3, travels over front and rear rollers marked respectively 75, 76, the latter roller being adjustable vertically by adjustment of its shaft in vertical slots 78a in the supports 78, as shown in Fig. 2. The front roller 75 may be a part of the associated folding machine 19, although of course it may be incorporated in and be a part of the stacker itself, if the latter is used independently of a folding machine. As shown, the front roller 75 is actually a portion, a reduced diameter, of a roller 75a of larger diameter around which travel belts 75b coming from and driven by the folding machine.

The upper stretch of belt 74 is slightly inclined to the upper surface of the stack lifting plates, 45 when the latter are in their lowermost position, and actually intersects that surface midway between the front or left end of the lifter plate (Fig. 2) and the rear end thereof, the belt gradually rising above the lifter plate toward the fixed stop 90 at its rear or right-hand end. Also, it will be observed from Fig. 6 that roller 75 is of smaller diameter than roller 75a. The purpose is to slow up the speed of the articles as they are introduced or fed into the stacker from the folder conveyor. Heavy articles, such as hand or buck towels, have sufficient momentum to carry them all the way back into the stacker. Therefore, as they slide along the lifting plate, their speed is reduced when they first enter, and the slower

moving conveyor belt 74 further slows them and delivers them to their final home position clear at the back end of the stacker. In the case of light or small articles, the rising belt 74 insures their travel all the way into the stacker, against stop 90. By adjusting the shaft of roller 76 vertically in the slots 78a, in the manner before described, more or less of the conveyor length may be made effective upon articles being advanced, this adjustment thus contributing to accurate feed of the articles up to and against the stop, without buckling or wrinkling.

A set of bridging fingers 79 is pivotally attached to the forward edge of each of the lifter plate sections 46 as shown in Figs. 5 and 6. Each 75 lifter plate is provided with a bracket 80 on which

is fixedly mounted a tubular bearing member 81. Through this extends a shaft 82 provided at each end with a collar 83 to which one of the bridging fingers 79 is rigidly secured, as by welding or brazing. Each bridging finger assembly is biased in a counterclockwise direction, Fig. 5, by a tension spring 84 extending from an arm 85 on one of the collars 83 to a fixed point 86 on the frame. Thus the several fingers 79 are yieldingly pressed against a cross rod 87 mounted either in the stacker or in the associated folder. In Fig. 5, it will be understood that the lifter plates 46 are nearing their lowermost position, but are not yet fully down, as will be noted and explained later.

Articles to be stacked are delivered to the stacking machine from the folding machine, one by one or in sequence, by the constantly moving belts 75b.

The present machine is so arranged as to prevent any possibility of the next article, coming from the folder, being advanced into the stacker below the lifting plates before the lifting plates have reached their lowest position. Such an article rides up upon the bridge fingers 79 and is led to its place upon the lifting plates, even though they are not fully down, as shown in Fig. 5.

Also, as the article reaches and is transferred to the lifting plates 46, it at first slides over the same, with some reduction in speed, due to friction on the plates, and then with further reduction in speed, due to the slower travel of belt 74, upon which it rides to its final position, against stop 90, ready for stacking. Outwardly bent end portions 88 of side guide plates 89 assist in guiding it to place, these guiding plates being provided with slots or openings 89a, through which fingers 45 move.

The article remains in place on the lifting plate until the solenoid 38 before referred to is again energized to initiate new stacking operations. At that time the lifting and supporting plates 46, 45 are in the full line positions, Fig. 1.

Energyization of solenoid 38 withdraws roller 29 from cam 41 and releases sleeve 22 for movement to the right, Fig. 1, thus closing the clutch. Shaft 17 therefore turns said sleeve for one complete revolution, or until the same cam again engages the roller 29 (now released by the solenoid) and returns the sleeve to its former position and opens the clutch. Cams 42, 43 and 44 are wide enough to permit the necessary sleeve motion.

During the single revolution of sleeve 22 these events occur:

During the first 90° of rotation, the cams 42, 44, elevate arms 51 and fully retract the stack supporting plates or fingers. These move outwardly to their dotted line positions, Fig. 1, with very little lift, because shafts 50 are directly beneath the stack supporting portions of fingers 45 and well within the outer edges of the lifting plate. By the time fingers 45 are withdrawn, the lifting plates 46, carrying the next article, have been elevated by cam 43 to the position marked "A" Fig. 1, just below the fingers 45. The ends of the two sets of fingers are quite close to each other, when they are advanced, thus supplying wide and full support to the stack and preventing it from sagging at the middle. As the fingers separate they allow the stack to be deposited upon the rising lifting plates.

During the second 90°, the supporting fingers or plates remain retracted, while the lifter plates

continue their upward motion to the positions shown at "B," at a level above the supporting fingers.

During the third 90° the lifting plates dwell, or remain stationary, holding the stack, while the cams 42, 44, advance or return the supporting fingers to their original positions, but now beneath the lifting plates.

During the final 90°, the fingers of course remain advanced while the cam 43 permits the lifter plates to descend to their original positions, thus depositing the stack upon supporting fingers 45, where it was before, but this time with another article added to the bottom of the pile.

During the described stacking operation, if a following article follows the first too closely and the parts reach a position, as shown in Fig. 5, with article X ready to advance upon the lifting plates before they are fully down, such an article rides to place over the bridging fingers 79, as before described.

Both the supporting fingers and lifting plates are more or less directly operated by cams on the sleeve 21, with minimum connecting mechanism, and thus are dependable and not likely to get out of order. Horizontal movement of fingers 45 prevents unnecessary disturbance of the stack, while yielding guide post members 70 assist in keeping it straight and prevent it from toppling. The mechanism is also equally effective upon both thin or limp articles and thick or heavy ones.

Other advantages of the invention will be apparent to those skilled in the art.

What I claim is:

1. Stacking apparatus, comprising a stack lifting plate, means for supporting a stack of articles above said plate, and an endless conveyor for advancing an article along said plate to stacking position, the upper stretch of said conveyor extending in the direction of article advance from a point below to a point above said plate.

2. Stacking apparatus, comprising a stack lifting plate, means for supporting a stack of articles above said plate, parallel, endless conveying members for feeding an article to and across the plate to stacking position thereon, means for reciprocating the plate vertically to deliver the articles fed to it to the stack, and bridging fingers attached to the plate near its article receiving edge and extending downwardly between said members for preventing articles fed to the plate from advancing to a position beneath it.

3. Stacking apparatus, comprising a stack lifting plate, means for supporting a stack of articles above said plate, parallel, endless conveying members for feeding an article across the plate to stacking position thereon, the upper stretch thereof being inclined upwardly from a point below to a point above the plate, means for reciprocating the plate vertically to deliver the articles fed to it to the stack, and bridging means attached to the plate near its article receiving edge for preventing articles fed to it from advancing to a position beneath the plate, said bridging means comprising a plurality of fingers pivoted to that edge of the plate lying above the conveying members and extending downwardly between said members toward the advancing articles to thereby receive their leading edges and compel them to ride up over the bridging fingers to a position above and upon the plate.

4. Stacking mechanism of the character de-

scribed, comprising a frame, a lifting plate vertically movable in the frame, oppositely disposed stack supporting members located above the lifting plate and movable toward and from each other, a horizontal shaft located below the lifting plate, means for continuously rotating said shaft, a sleeve movable endwise upon the shaft and provided with cam means for operating said lifting plate and stack supporting members, and clutch means operated by endwise sleeve movement for coupling and uncoupling the sleeve and shaft.

5. Stacking mechanism, comprising a frame, a lifting plate vertically movable in the frame, oppositely disposed stack supporting members located above the lifting plate and movable toward and from each other, said lifting plate having a depending post, and two sets of oppositely disposed grooved rollers engaging opposite sides of said post and serving to support and guide the same, one set of said rollers being mounted in fixed position upon the frame, and a support for the other set of rollers movably mounted upon the frame for adjustment of the second set toward and from the first set.

6. Stacking mechanism of the character described, comprising a frame, a lifting plate vertically movable in the frame, oppositely disposed stack supporting members located above the lifting plate and movable toward and from each other, a transverse shaft located below the lifting plate for operating the same, an endless belt conveyor having its upper stretch extending from side-to side of the lifting plate for advancing an

article across it, a feed belt for delivering articles to the conveyor, and a roller shaft common to said belt and conveyor and having roller portions supporting both, the roller portion for the conveyor being of smaller diameter than that for the belt, to thereby reduce the speed of articles being advanced to stacking position.

7. Stacking apparatus, comprising a stack lifting plate, means for supporting a stack of articles above said plate, an endless conveyor for advancing an article along said plate to stacking position, the upper stretch of said conveyor extending in the direction of article advance from a point below to a point above said plate, and means whereby the delivery end of the upper conveyor stretch may be adjusted vertically to vary the length of that portion of the conveyor extending above the plate and effective upon the articles being advanced.
